(No Model.)

P. A. LAWYER.
CARPET STRETCHER.

No. 593,898.

Patented Nov. 16, 1897.

UNITED STATES PATENT OFFICE.

PHILIP ARTHUR LAWYER, OF JANESVILLE, ILLINOIS.

CARPET-STRETCHER.

SPECIFICATION forming part of Letters Patent No. 593,898, dated November 16, 1897.

Application filed May 27, 1897. Serial No. 638,430. (No model.)

To all whom it may concern:

Be it known that I, PHILIP ARTHUR LAWYER, a citizen of the United States, residing at Janesville, in the county of Coles and State 5 of Illinois, have invented certain new and useful Improvements in Carpet-Stretchers; and I do hereby declare the following to be a full, clear, and exact description of the invention, such as will enable others skilled in the art to 10 which it appertains to make and use the same.

My invention, as will be hereinafter fully described and claimed and illustrated in the accompanying drawings, relates to certain new and useful improvements in carpet-stretching appliances, the object being to produce a simple and reliably efficient device of the character specified which will enable the operator to thoroughly stretch the carpet in its position ready for being permanently secured without the necessity of being assisted by an attendant, the entire operation of 15 stretching and permanently securing being made easily possible for one person to accomplish.

20 A further object is to produce a device of the character specified which may be very cheaply constructed and placed upon the market at a nominal price.

In the accompanying drawings, Figure 1 is 25 a perspective view of my invention as applied to use. Fig. 2 is a perspective detail thereof on a slightly-enlarged scale. Fig. 3 is a vertical section of parts of the device. Fig. 4 is a front view of the anchoring attachment. Fig. 5 is a detail of one of the carpet-engaging teeth.

30 Reference to the various details of my invention will be made by figures, the same figure being employed to designate the same 40 part throughout the views.

In carrying out my invention I provide the cross-head 1, having the anchoring-stem 2 and the retaining-jaw 3, the latter being provided upon its under side with a series of 45 preferably outwardly-curved teeth 4, designed to take into the hem or other portion of the carpet and engage the same without fear of mutilation.

Pivotedly connected to the anchoring-stem 50 2 by means of the link 5 is the lever 6, which provides a handle for the operator. The lower end of the lever is provided with the

anchoring teeth or points 7, which may be cheaply made from a single piece of wire properly bent upon itself to form the loop 8, 55 as shown in Fig. 4, the device being secured in the recess 9 by retaining-nuts 10 and bolts 11 therefor, the latter taking through the lever to insure a reliable union of the parts.

The teeth 4 are so constructed that they 60 may be easily anchored in position in the cross-head by means of anchoring-bolts and nuts 12. In Fig. 5 I have illustrated a detail of the teeth, which consists of the sharpened ends or points 13 and the lateral loop 14, 65 through which is designed to pass the retaining-bolt 12, thus insuring against the casual displacement of the teeth.

It will be understood that any preferred 70 and suitable material may be employed in constructing my improved carpet-stretching appliance and that various sizes thereof may be adopted to meet the requirements in different cases.

While I have shown the preferred construction 75 to be adopted in producing my improved carpet-stretching appliance, yet I desire it to be understood that the equivalent of such construction is comprehended by me, and I do not wish to be confined strictly to the exact 80 act showing I have made.

In the central portion of the front edge of the retaining-jaw 3 I form the recess 15, designed to accommodate or receive the lower end of the operating-lever 6 and the anchoring-points 7. In order that the strength of the jaw 3 may not be impaired, I locate the binding plate or wire 16, which reaches across the recess 15, occupying the same plane as the front edge of said jaw, while the ends of 85 said plate are bent at right angles and take entirely through said jaw on either side of the anchoring-stem 2, said ends being properly secured by upsetting or a suitable nut therefor.

90 The operation of my improved carpet-stretching appliance may be stated to be as follows: The teeth 4 are caused to engage the edge of the carpet when the points 7 are entered in the floor at a point in advance of the jaw, when by moving the lever from him the operator is enabled to draw the jaw 3 and the carpet with which it is engaged toward 95 said points 7, which position may be readily

maintained by placing the foot upon the anchoring-stem 2, when the points 7 may be disengaged from the floor and a new purchase taken in advance of the jaw and the operation repeated until the carpet is adjacent to the wall or in position to be permanently secured by tacking, when the lower end of the lever, with its anchoring-points 7, is raised and entered in the recess 15 between the end 10 of the stem 2 and the plate 16. After the lower end of the lever is entered in the recess 15 the anchoring-points 7 may be caused by a few blows upon the lever 6 to take into the floor sufficiently to reliably anchor the 15 cross-head in its adjusted position, when the carpet may be permanently secured. By thus providing means for anchoring the device in an adjusted position the operator is enabled to leave the stretching appliance and permanently secure the carpet. After this part of 20 the carpet has been nailed in position the points 7 are withdrawn and the entire device removed to an adjacent section of the carpet to be stretched, when the operation may be 25 repeated. It will therefore be apparent that I have produced a simple though thoroughly reliable device of the character specified which may be manufactured and sold at a comparatively small price, and believing that 30 the operation, advantages, and construction of my improved carpet-stretching device have been made fully apparent further reference is dispensed with.

Having thus fully described my invention, 35 what I claim as new, and desire to secure by Letters-Patent, is—

1. A carpet-stretcher consisting of a stem provided with a cross-head having a carpet-engaging jaw carrying removable teeth, means to retain the teeth in place, a recess in the 40 central front edge of the cross-head and a plate extending across the recess, a lever pivoted to the stem having teeth in its end, all combined as set forth.

2. A carpet-stretcher, consisting of a stem 45 provided with a cross-head having a carpet-engaging jaw carrying teeth, a recess in its front edge inclosed by a plate, a lever pivoted to the stem having a recess in its outer end, removable teeth in said recess and means 50 to retain them in place, all combined as set forth.

3. The herein-described carpet-stretching appliance consisting of a cross-head having the carpet-engaging jaw and anchoring-stem 55 disposed at right angles thereto, said jaw having the recess in its forward edge and further provided with the reinforcing-plate; an operating-lever pivotally secured to said stem and having anchoring-teeth secured to its 60 lower end, and a series of carpet-engaging teeth mounted in said jaw, each tooth having a sharpened engaging point and a laterally-curved anchoring-bolt-engaging section, all operatively combined in the manner and for 65 the purpose set forth.

In testimony whereof I affix my signature in presence of two witnesses.

PHILIP ARTHUR LAWYER.
